UNITED STATES PATENT OFFICE.

GEORGE H. MILLER, OF LIMA, ILLINOIS.

PENDULUM-BOB.

1,175,793.

Specification of Letters Patent. Patented Mar. 14, 1916.

Application filed November 29, 1913. Serial No. 803,839.

To all whom it may concern:

Be it known that I, GEORGE H. MILLER, a citizen of the United States, residing at Lima, in the county of Adams and State of Illinois, have invented new and useful Improvements in Pendulum-Bobs, of which the following is a specification.

This invention relates to pendulum bobs, the object in view being to provide a bob having a section detachably connected to the remainder of the bob and threaded on the rod, so as to be adjusted up and down on the rod and held against rotation by means of the major portion of the bob, when brought into its proper relation to the removable section, the device being intended as a whole for adjusting the bob up and down on the rod in order to regulate the clock mechanism.

With the above and other objects in view, the invention consists in the construction, combination and arrangement of parts, as will be hereinafter more fully described, illustrated in the accompanying drawings, and pointed out in the claim hereunto appended.

In the drawings: Figure 1 is a front elevation of a pendulum bob and rod, showing the normal relation of the two parts of the bob. Fig. 2 is a similar view, showing the major portion of the bob elevated, in order to enable the smaller section thereof to be adjusted on the rod. Fig. 3 is a vertical section through the bob taken in line with the rod. Fig. 4 is a detail view of the removable section.

Referring to the drawings, 1 designates a pendulum bob, and 2 the rod by which said bob is carried.

In carrying out the present invention, the

bob 1 is provided with a removable section 3 in the lower edge or margin thereof, and said removable section 3 is internally threaded so as to screw upon the lower end of the rod 2, which is also threaded, as shown at 4.

In order to adjust the bob 1, the larger section thereof is slid upward on the rod or stem 2, and the smaller section 3 thereof is then threaded upward or downward on the rod 4, a suitable distance, after which the larger section 1 of the bob is lowered until it encompasses the smaller section 3 thereof, which acts as a lock for the section 3 and prevents the latter from turning on the rod, thereby fixing the adjustment. It will thus be observed that it is a comparatively easy and simple matter to adjust the bob as a whole lengthwise of the rod 2, for the purpose of regulating and timing the clock movement.

What is claimed is:

The combination with a pendulum rod, of a circular bob embodying a main section formed with a recess in the margin thereof, said recess having two parallel sides, and a removable bob section threaded and adjustable on said rod, the main section of the bob being slidable on the rod in order that the two sections may be entirely separated one from the other to enable the smaller section to be turned on the threaded rod, both of the sections when in their useful position having flush surfaces.

In testimony whereof I affix my signature in presence of two witnesses.

GEORGE H. MILLER.
